UNITED STATES PATENT OFFICE.

LEO S. NAFZIGER, OF GOSHEN, INDIANA, ASSIGNOR TO SHEET METAL SPECIALTY COMPANY, OF GOSHEN, INDIANA, A CORPORATION OF INDIANA.

EXTENSION AND ROOF FOR SILOS.

1,102,201.

Specification of Letters Patent. Patented June 30, 1914.

Application filed June 17, 1913. Serial No. 774,201.

To all whom it may concern:

Be it known that I, LEO S. NAFZIGER, a citizen of the United States, residing at Goshen; in the county of Elkhart and State 5 of Indiana, have invented certain new and useful Improvements in Extensions and Roofs for Silos, of which the following is a specification.

This invention relates to attachments for 10 silos and particularly to a combined extension and roof.

It is a well known fact that after a silo has been filled, the ensilage will settle from 15 five to seven feet. As silos cost on an average of \$5.00 per foot, the owner is investing from twenty-five to thirty-five dollars in silo space which is really of no value. To overcome this some farmers fasten poultry wire around the top of the silo to serve as a 20 temporary retainer, and then fill to the top of the wire in order to insure having a full silo after the ensilage has settled. Even this makeshift is impossible in silos provided with the ordinary form of roof. Fur- 25 thermore, the ordinary roof is in the way while the silo is being filled as it interferes with the operators who trample the ensilage in order to pack it firmly. At the same time a roof is really needed in order to exclude 30 rain and snow from the silo.

The present invention has therefore been designed to obviate the objectionable features of the various alternative structures now in use.

35 The object of the invention is to provide a structure adapted to be secured upon the upper end of a silo and which when in its expanded position will serve as an extension for the silo to enable it to contain a sufficient 40 amount of ensilage to allow for the inevitable settling, and which may be collapsed to form a roof or cover for the silo.

An important object is to provide a structure of this character which will be rigid 45 when in its expanded position so that there will be no danger of the walls spreading under pressure of the ensilage, and which will have its joints so protected and formed as to prevent the entrance of water into the silo.

50 Other objects and advantages such as cheapness, simplicity, durability, efficiency and the general improvement of the art will

be fully brought out in the following specification and illustrated in the accompanying drawings in which:

55

Figure 1 is a perspective view of the invention applied to a silo and in its expanded position, Fig. 2 is a fragmentary horizontal sectional view therethrough, Fig 3 is a fragmentary vertical sectional view, Fig. 4 is a perspective view of the device showing portions in the expanded position, and other portions collapsed, and Fig. 5 is a perspective view of the entire device collapsed to form a roof.

65

Referring more particularly to the drawings, the numeral 1 designates the upper portion of a silo to which my combination extension and cover is adapted to be connected.

70

My improved device comprises an annular ring 2 formed of similar sections 3 which overlap each other and are connected as by bolts or rivets 4. Each of the sections 3 comprises a horizontal portion 5 adapted to seat and be secured upon the rim of the silo as by bolts, nails or spikes. From the horizontal portion 5 an inclined portion 6 extends downwardly to serve as a watershed. The vertical portion 7 is formed integrally with the portion 5 and is adapted for connection with the members to be described. At the points of union of the successive sections 3 angle braces 8 are secured for strengthening the structure.

75

Hingedly connected with the vertical portions 7 of the sections 3 as by hinges 9 are upstanding members 10 and 11 formed preferably of sheet metal and in the shape of an isosceles triangle. Upon each side of the members 10 are connected by means of hinges 12 similar but inverted members 13 which occupy the spaces between the members 10 and 11. In order to form a perfect fit between these different members, I provide flanges 14 adjacent each side edge of the members 11 which co-act as shown with flanges 15 formed on the adjacent edges of the members 13. The members 10 are provided with strips 16 which overlap the joint between the members 10 and 13. Flanges 17 are formed on the strips 16 for a purpose to be described. In order to prevent the members 13 and 11 from becoming disengaged

80

85

100

and to prevent them from moving outwardly I provide bars 18 pivoted as at 19 upon the members 11. These bars are provided adjacent their ends with oppositely disposed slots 20 adapted to engage pins 21 secured upon the members 13. One of the members 10 is provided with an opening closed by a removable cap 22 for a purpose to be described.

10 When the device is in the position illustrated in Fig. 1, it is adapted for use as an extension of the silo walls, so that sufficient material may be placed therein to allow for the subsequent settling. In this position 15 the members 10 and 11 together with the members 13 are vertically disposed with the flanges 15 on the members 13 interlocked with the flanges 14 on the members 11, and the junctions of the members 10 and 13 covered by the strips 16. When ensilage is placed within the device there will be considerable outward pressure on the wall formed by the interlocked sector members. By disposing the bars 18 horizontally as 20 shown in Fig. 1 with the slots 20 in engagement with the pins 21 it will be obvious that spreading of the wall sections will be effectively prevented.

In order to adapt the device for use as a 30 roof it is merely necessary to swing the bars 18 into a vertical position as shown at the left of Fig. 4, whereupon the members 13 and 11 may be separated by disengaging the flanges 14 and 15. The members 13 may 35 then be swung inwardly upon the hinges 12 and disposed radially of the device as shown at the left of Fig. 4. The members 11 and the members 10 carrying the members 13 may be swung downwardly until their edges 40 meet and they are disposed in the form of a cone, as shown in Figs. 4 and 5. The flanges 14 may then be interlocked with the flanges 17 formed on the strips 16, thus making the joints entirely protected. This joint 45 obviates the danger of leakage of water into the silo and thus keeps the ensilage dry. After the members have been swung inwardly and interlocked a cap 23 is placed at the apex of the resulting cone, and secured firmly in position as by means of 50 bolts or the like.

During the fermentation of the ensilage which naturally occurs considerable gas is evolved which may be allowed to escape by 55 removing the cap 22.

While the members 10 are described as provided with strips 16 having flanges 17 formed thereon it might be found expedient to form the flanges integrally upon the 60 side edges of the sections 10.

Having thus described my invention what I claim is:

1. A combined extension and roof for silos comprising a ring secured upon the 65 per edge of a silo, a plurality of triangular

members hingedly secured upon said ring, other triangular members hingedly secured upon the edges of certain of said first named triangular members, flanges on the edges of said first named triangular members, and flanges on the free edges of said second named triangular members, certain of said flanges being adapted to overlap when the members are in their expanded positions, and certain of said flanges being adapted to overlap when the members are in their collapsed positions for forming watertight joints. 70 75

2. A combined extension and roof for silos comprising a ring secured upon the upper end of a silo, a plurality of triangular members hingedly connected with said ring, a pair of triangular members hingedly secured upon the edges of each alternate one of said first named members, means for interlocking said members when in their expanded positions and means for interlocking certain of said members when in their collapsed positions for forming tight joints. 80 85

3. A combined extension and roof for silos comprising a plurality of triangular members hingedly secured upon the upper edge of a silo, outwardly and inwardly bent flanges formed on the side edges of each alternate one of said members, a pair of triangular members hingedly connected with the side edges of each of the other alternate members, outwardly, inwardly then outwardly bent flanges on the side edges of the last named members, and outwardly 90 95 bent flanges on the free edges of each of said pairs of members, said first and second named flanges being adapted to interlock when the device is in its collapsed position, and said second and third named flanges being adapted to interlock when the device is in its expanded position. 100 105

4. A combined extension and roof for silos, comprising a plurality of triangular members hingedly secured upon the upper edge of a silo, flanges on the side edges of each alternate one of said members, a pair of triangular members hingedly secured upon the side edges of each of the other alternate members, flanges on the side edges 110 115 of said last named members, and flanges on the free edges of said pairs of members, said first and second named flanges being adapted to interlock when the device is in its collapsed position, and said second and third named flanges being adapted to interlock when the device is in its expanded position. 120

5. A combined extension and roof for silos, comprising a plurality of triangular members hingedly secured upon the upper edge of a silo, flanges on the side edges of each alternate one of said members, a pair of triangular members hingedly secured upon the side edges of each of the other alternate members, flanges on the side edges 125 130

of said last named members, flanges on the free edges of said pairs of members, said first and second named flanges being adapted to interlock when the device is in its collapsed position, and said second and third named flanges being adapted to interlock when the device is in its expanded position, and a cap adapted to be secured upon the ends of said first named members for form-

ing a closed structure when the device is in its collapsed position.

In testimony whereof I hereto affix my signature in the presence of two witnesses.

LEO S. NAFZIGER.
